UNITED STATES PATENT OFFICE.

WILLIAM H. BURK AND LEE M. RIGBY, OF FOSTORIA, OHIO, ASSIGNEES OF ONE-THIRD
TO JOSEPH HODGKISS, OF FOSTORIA, OHIO.

LIQUID-FUEL BURNER.

992,404.

Specification of Letters Patent. Patented May 16, 1911.

Application filed July 28, 1910. Serial No. 574,313.

To all whom it may concern:

Be it known that we, WILLIAM H. BURK and LEE M. RIGBY, citizens of the United States, residing at Fostoria, in the county of 5 Seneca, State of Ohio, have invented a new and useful Liquid-Fuel Burner, of which the following is a specification.

This invention has reference to a burner designed more particularly for using crude 10 oil; and it is the object of the invention to provide a novel and perfect form of burner for this purpose, in which the oil is fed in drops through a tube into a bowl in which combustion takes place, the oil being 15 vaporized upon coming in contact with the heated wall of the bowl.

The invention also has for its object to provide perfect means for feeding air into the tube, this air commingling with the oil 20 dropping through the tube, and passing therewith into the bowl.

A further object of the invention is to provide a structure of the kind stated which is simple and without complicated parts, 25 and also to provide the tube through which the oil drops, with a sight glass, through which the feed may be observed.

Other objects and advantages of the invention will be apparent when the nature 30 of the same is better understood, it consisting in the combination and arrangement of parts to be hereinafter described and claimed.

The invention is illustrated in the accompanying drawing forming a part of this 25 specification, in which—

Figure 1 is a central vertical section of the burner and part of a stove. Fig. 2 is a horizontal section on the line 2—2 of Fig. 1.

In the drawing, 5 denotes the top of the 40 heater or stove to which the burner is applied. In the bottom of the stove, on the grate, or any other suitable place, is mounted a bowl 6 having a central raised portion 7 which serves as a spreader for the oil, as 45 will be presently described.

Depending from the stove top 5, is a downwardly tapered tube 10. This tube is open at the top and its lower end is also open, this end of the tube extending sufficiently into the bowl 6 so that it is brought 50 in close proximity to the apex of the spreader 7, the latter being so located beneath the lower open end of the tube, that the oil passing through the tube drops on 55 the spreader. At the top of the tube 10 is

an outstanding annular flange 9 which seats in an opening in the stove top and thus serves to support the burner.

Mounted over the upper open end of the tube 10, is a cylindrical air chamber 11 the 60 opposite sides of which are entered by air conducting pipes 12, said pipes extending in an upward curve from the air chamber, and having their outer ends fitted with suitable dampers 13 for controlling the 65 amount of air entering the pipes.

The lower end of the air chamber 11 is open, and has a reduced and tapered portion 14 which fits snugly in the upper open end of the tube 10, the taper of the part 14 70 corresponding to the taper of the tube. The reduced lower end of the air chamber forms an external shoulder 15 which engages the top edge of the tube 10, and thus serves as a support. The top of the air chamber 11 is 75 formed with a nipple 16 to which is fitted a bulb 17 of glass or other transparent material.

At 18 is indicated a reservoir containing the crude oil. A pipe 19 is connected to 80 this reservoir, said pipe leading to the burner, adjacent to which it terminates in a downward bend 20 extending into the bulb 17 through the top thereof. The reservoir 19 is suitably elevated and located to give 85 a gravity feed. In the pipe 19 is interposed a valve 21 for controlling the flow of oil therethrough. In the flange 9 is an opening 22 which is closed by a slide 23. This opening is provided in order that a piece of 90 burning paper or other material may be dropped into the bowl 16 for the purpose of starting the burner.

In operation, the valve 21 is opened, and a small quantity of oil is permitted to drop 95 into the bowl 6. The valve 21 is then closed, and a piece of burning paper or rag is dropped through the opening 22 into the bowl, to ignite the oil therein. The burning oil quickly heats the bowl, so that when 100 the valve 21 is again opened, and the oil drops into the bowl, it is at once vaporized and ignited. The oil is fed drop by drop into the bowl, and upon striking the spreader 7 it is distributed by the latter to facilitate 105 the vaporization. Air to support combustion passes down the tube 10 with the oil, and is mixed with the oil vapor, thus producing a highly combustible mixture. The air enters the tube by the way of the pipe 110

12 and the air chamber 11, the amount of air being controlled by the dampers 13. By the tapered form of the tube 10, the air is discharged with greater force into the bowl 6, and a more thorough commingling of the air and oil vapor is thereby effected. The drops of oil are visible through the bulb 17, in view of which the feed may be observed at all times, and therefore kept under perfect control.

10 What is claimed is:

A fuel burner comprising a bowl having a central upstanding portion, a tapered tube having one end dipping into the bowl to

15 a point near the bottom thereof, an air chamber secured to the upper end of the tube and provided with upwardly curved air supply pipes, dampers controlling the pipes, a bulb secured to the air chamber, and means for supplying liquid fuel to the bulb.

20 In testimony that we claim the foregoing as our own, we have hereto affixed our signatures in the presence of two witnesses.

WILLIAM H. BURK.
LEE M. RIGBY.
